HEEL DOWEL CONSTRUCTION

William O. Burke, Rockford, and Robert Z. Buntic, Elmhurst, Ill., assignors to National Lock Co., Rockford, Ill., a corporation of Delaware

Filed Oct. 18, 1963, Ser. No. 317,243

6 Claims. (Cl. 36—34)

The present invention relates to a shoe heel and more particularly to a replaceable lift construction including a novel heel dowel for attaching the lift to the heel of a woman's shoe.

Fashionable designs in women's shoes in recent years have tended more to those generally referred to as spike heels which have a very small cross section at the ground engaging end or heel lift. The heels require lifts at the lower ends or tips which have substantially greater wearability than the material forming the heel and can be easily replaced when worn to provide an inexpensive means of preserving the condition and appearance of the heel of the shoe.

Lifts have been made of leather which are nailed directly to the heel or of a relatively tough hard plastic molded onto a dowel or other suitable means of attaching the lift to the heel. Recently, lifts have been formed of more resilient plastic material or natural or synthetic rubbers of a relatively flexible characteristic. These materials are molded onto heel dowels having heads with an annular groove or undercut surface in an endeavor to provide additional engagement between the lift material and the heel dowel.

An important object of the present invention is the provision of a novel heel dowel construction having an enlargement or head so constructed and designed as to effect a positive interlock with the molded material utilized to form the heel lift. The heel dowel head is a cylindrical cup with slots cut in its side walls to form vertically spaced upper and lower annular flanges. The lift material envelopes the head and flows through the slots and into the central recess of the cup to form a most effective mechanical interlock with the head. This mechanical interlock has been found to be far superior to prior heel dowels having an annular groove around the head since the lift material flowing or projected into the groove may be easily and readily withdrawn so that the lift becomes disengaged from the heel dowel under pressure.

A further important object of the present invention is the provision of a novel heel dowel affording increased structural adequacy against impact forces normally imposed in use. The novel heel dowel comprises a cylindrical cup member slotted to provide vertically spaced annular flanges with the upper and lower annular flanges engaging the resilient lift material in laminar fashion, so that the upper annular flange reinforces the lower annular flange absorbing a portion of the stresses imposed thereon and transmitting them on to the dowel shank. Furthermore, the flat top surface of the upper annular flange is separated from the lower surface of the heel by a layer of the resilient lift material thereby providing a cushioning effect which absorbs impact shock and prevents a portion thereof from being transmitted into the heel.

Another important object of the present invention is the provision of a heel dowel having a head capable of being formed of smaller dimensions than prior known heel dowels and yet effect a greater retention or holding power with the lift than with prior known dowels. Thus, the present heel dowel is more versatile and can be utilized on the smaller heels and ground engaging lifts without reducing the conventional shank diameter of the dowel.

A further object of the present invention is the provision of a heel dowel capable of presenting a greater thickness of wearing material below the lower surface of

2

the head of the dowel than in prior structures without sacrificing the greater holding power or retentive capability between the lift material and the heel dowel. Consequently, replacement of the lifts will occur at less frequent intervals than with prior known dowels resulting in longer life.

The present invention also comprehends the provision of a heel dowel which is inexpensive to make and to which may be easily and most effectively molded a plastic or resilient lift to provide a heel lift assembly which is easily and quickly attached to a shoe heel by driving and anchoring the shank of the dowel into a preformed hole in the heel.

The present invention further comprehends the provision of a heel dowel having a head formed as a cylindrical cup with slots cut in its side walls providing greater interlocking flow areas than comprehended in prior dowels and thereby provide a more secure interlock between the molded lift material flowing into and through these connected openings and the head of the heel dowel.

Thus, the disclosed novel embodiment of a heel dowel, as compared to prior forms of heel dowels, has numerous advantages thereover among which are the following:

(1) The cup-shaped slotted head is smaller in diameter or cross section affording; (a) smaller heel sizes, (b) more lift material around the head of the dowel, (c) more lift material under the head of the dowel.

(2) Transverse slots opening into the hollow head, which slots are substantially larger in area affording a more effective interlock between the dowel head and the lift material.

(3) More effective structurally due to reinforcing effect of upper flange.

(4) The upper annular flange affords additional envelopment of the dowel head by the lift material.

Further objects are to provide a construction of maximum simplicity, efficiency, economy and ease of assembly and operation, and such further objects, advantages and capabilities as will later more fully appear and are inherently possessed thereby.

In the drawings:

FIGURE 1 is a view partially in vertical cross section of a heel for a woman's shoe having the heel dowel and lift of the present invention affixed to the heel.

FIG. 2 is an enlarged fragmentary view of the lower end of the heel shown in FIG. 1 with the heel dowel and lift applied thereto.

FIG. 3 is a horizontal cross sectional view taken on the line 3—3 of FIG. 2 and viewed in the direction of the arrows, showing the interlock between the lift and the head of the heel dowel.

FIG. 4 is a horizontal cross sectional view taken on the line 4—4 of FIG. 2 and viewed in the direction of the arrows.

FIG. 5 is a vertical cross sectional view taken on the irregular line 5—5 of FIG. 3 to further show the construction of the head of the heel dowel.

FIG. 6 is a fragmentary view, part in side elevation and part in vertical cross section, of the headed end of the heel dowel.

Referring more particularly to the drawing wherein is disclosed an illustrative embodiment of the present invention, FIG. 1 discloses a heel 10 formed of a plastic composition or other suitable material having an upper surface 11 shaped to conform to the configuration of lady's shoe with the heel body narrowing to a lower end 12 of a relatively small cross sectional area. A heel lift member 13 is attached to the lower end 12 to provide the ground or floor engaging surface for the heel.

The lift member includes a heel dowel 14 having an elongated shank or stem 15 which is inserted into an elongated performed hole or bore 16 in the heel 10 and

an enlarged head 17 through and around which the lift material 18 is molded. The lift is formed from a movable, relatively soft yet tough resilient material which provides greater resistance to wear and a cushioning effect for the user than obtained with prior materials. Such a lift material may be a resilient but long wearing plastic composition or a natural or synthetic rubber, such as polyurethane rubber.

The elongated shank or stem 15 has a generally conical pointed end 19 which is inserted into the heel 10 and longitudinally extending knurling 21, and spaced axially therefrom, a relatively short knurled portion 22. The knurled portions 21 and 22 prevent the dowel 14 from turning when driven into an opening in the heel body and aid in securing the lift member 13 to the heel as the knurled portions are preferably of a slightly greater diameter than the diameter to the preformed hole or bore 16.

The opposite end of the shank terminates in an enlarged hollow head 17 with an intermediate cylindrical portion 23 of slightly larger diameter than the shank 15 between the hollow head and shank. The enlarged hollow head 17 is shown formed as a cylindrical cup slotted to provide an upper annular flange 25 vertically spaced from a lower annular flange 26. A relatively large central recess 27 extends axially through the enlargement or head from the lower annular flange 26 as shown in FIGS. 5 and 6, and opposed relatively deep slots 28, 28 extend through the hollow head or cup where they provide relatively large radially extending openings between the vertically spaced flanges 25 and 26 communicating with the central recess 27 between the residual connecting web portions 29.

The sides of these slots 28 are parallel and each provides an arcuate opening to the central recess. The slotting operation removes substantially sectors of the side wall formed by the central recess of the cylindrical hollow head and provides axially spaced horizontally arranged parallel surfaces. The lift material 18 when molded about and through the enlarged hollow head 17 of the heel dowel 14 has its material flowing completely about and enveloping the head, and into the central recess 27 and through the large communicating opposed arcuate slots 28 to form an integral and connected body of material having a positive mechanical interlock with the head 17.

As clearly shown in the drawing, the resilient lift material completely encompasses and envelopes the projected cupped head 17 of the heel dowel whereby an upper layer 31 of the lift material 18 disposed between the upper surface of the upper annular flange 25 and the lower surface of the end 12 of the heel body, provides a cushioning effect which absorbs impact shock and prevents a portion of the shock from being transmitted into the heel proper.

Due to the small diameter or cross section of the head 17, a substantial thickness of the lift material 18 is disposed around and under the dowel head, thereby materially increasing the wearing qualities and life of the lift as well as absorbing impact shock to which the lift is subjected in use.

The present heel dowel utilized with the heel lift for the heel of a lady's shoe has the following important advantages:

(1) The head on the heel dowel is smaller in diameter or cross section than heel dowels presently known and thus adapted for use on smaller lifts and smaller heels.

(2) Provides more wearing material between the headed end of the heel dowel and the lower or ground engaging surface of the lift and, consequently, longer life before requiring replacement.

(3) The hollow interior or bore and the communicating transverse slots of the present heel dowel are larger in area and more effective in the retention of the molded lift than those of prior known devices.

(4) The present heel dowel is cheaper and easier to manufacture as the communicating transverse slots are made by broaching, milling or the like, and the recess or bore in the hollow cylindrical head cold headed or impact extruded, whereby any machining operations are reduced to a minimum.

Having thus disclosed the invention, we claim:

1. A heel dowel for mounting a moldable heel lift onto the heel of a shoe having a preformed opening therein, comprising an elongated shank for insertion into the preformed opening, and an integral hollow cylindrical head on the end of said shank having a central longitudinal cylindrical bore therein opening to the lower end of the head and radially extending slots formed in the periphery of the head intermediate its ends and intersecting and opening into said central bore to form vertically spaced annular flanges and a mechanical interlock between the heel lift and said cylindrical head where the heel lift material flows into and through said slots and said central longitudinal bore and completely envelops and interlocks with said head.

2. A heel dowel as set forth in claim 1, in which said central longitudinal bore extends upwardly into said head to adjacent the junction of said head with said shank.

3. A heel dowel as set forth in claim 1, in which the spaced annular flanges engage the lift material in laminar fashion with the upper annular flange reinforcing the lower annular flange and absorbing and transmitting imposed stresses to the shank of the dowel and a layer of lift material is disposed between the lower surface of the heel and the upper surface of the upper flange providing a cushioning effect and absorbing impact shock.

4. A heel dowel as set forth in claim 1, in which said slots formed in the periphery of the cylindrical head have substantially the configuration of sectors of an annulus.

5. In a heel lift assembly, the combination of a heel dowel having an elongated shank adapted to be inserted and anchored in an opening in the heel of a shoe and an integral hollow cylindrical head, and a heel lift molded into and enveloping said head and interlocked therewith to form an integral unit, said cylindrical head having a central longitudinal cylindrical bore extending from adjacent the junction of the head and the elongated shank to and opening in the lower end of said head and elongated generally radially extending opposed slots formed in the periphery of the head intermediate its ends intersecting and opening into the central longitudinal bore, said slots forming spaced upper and lower annular flanges each having outer diameters equal to the diameter of said head and inner diameters equal to the diameter of the central bore, said heel lift being formed of a moldable material completely enveloping the cylindrical head and extending into and through said elongated slots and said central cylindrical bore to provide a mechanical interlock with the head of the heel dowel, said lift material extending over the upper annular flange providing a cushioning means for absorbing impact shock and providing a substantial thickness of material around and below the head.

6. In a heel dowel assembly as set forth in claim 5, in which said elongated radially extending slots are separated by opposed residual web members forming part of the head and joining said upper and lower annular flanges.
